FIRE ALARM SYSTEM

Francis C. Evans, Richmond, N. Y., assignor to
American District Telegraph Company, Jersey
City, N. J., a corporation of New Jersey

Application July 20, 1950, Serial No. 174,898

2 Claims. (Cl. 340—227)

1

The present application is a continuation-in-part of application Serial No. 789,509, filed December 3, 1947, now abandoned. Application Serial No. 789,509 is a continuation-in-part of application Serial No. 423,131, filed December 16, 1941, now Patent 2,432,145, issued December 9, 1947.

This invention relates to fire alarm systems and more particularly to such systems employing thermocouple elements for the generation of potential to operate alarm devices.

The term thermocouple used in this specification and in the claims is to be construed as defining a literal thermocouple or a thermopile made up of a plurality of thermocouples.

In some installations employing thermocouples for the above purposes it will be found that the heating equipment employed in the premises is of such character as to cause the creation of false alarms, particularly where the heating equipment consists of blower type devices in which concentrated heat is projected into the protected space at intervals. For example, if a plurality of thermocouples are connected in series through alarm operating mechanism, and if a sudden blast of heat impinges upon such thermocouples, the generated potential may be sufficient to immediately actuate the alarm mechanism.

An object of the present invention is to provide compensation for a system of the above character whereby the effect of a concentrated blast of heat is ineffective to operate the alarm mechanism.

Another object of the invention is to provide mechanism which can be placed adjacent the heating element in such position that the effect of the heat blown from the element upon the compensating mechanism will balance the effect of the heat on the thermocouple elements.

Another object of the invention is to provide compensation as before described in which control of the effect of the compensating device can be maintained.

In carrying out the foregoing and other objects of the invention a fire alarm system employing the present improvements makes use of a plurality of thermocouples or thermopiles disposed about the premises to be protected, which premises has therein one or more heat dispersers of the type commonly known as blower heaters. Located in the path of dispensed heat and closely adjacent to the heating element is a unit made up of a thermocouple or thermopile with associated resistor or resistors which can be regulated to vary the effective potential output of

the thermocouple. The compensator thermocouple is connected in circuit with the alarm thermocouples in such fashion that potential generated by the compensator bucks the potential generated by the alarm thermocouples so that if such potentials are equal, no alarm will result. Such an arrangement has no deleterious effects on the efficiency of the system for fire alarm purposes since the alarm thermocouples are of such number that if an alarm condition arises the combined potentials of the alarm thermocouples will more than balance the bucking potential of the compensator thermocouple with the result that a potential of such value is fed to the alarm mechanism as to cause the operation of this mechanism for alarm purposes. In one type of compensator the adjustable resistor elements are connected in parallel to the thermocouple element for close adjustment while in another form of compensator element an adjustable resistor is connected in series with the thermocouple element for such adjustment. In either form of the invention the resistor or resistors can be eliminated from the circuit so that the full effect of the compensator thermocouple potential will be introduced into the circuit of the alarm thermocouples.

Other features, objects and advantages of the invention will become apparent by reference to the following detailed description of the accompanying drawings, wherein:

Fig. 1 is a front view of a conventional blower heater;

Fig. 2 is a plan view of a system associated with such a blower heater;

Fig. 3 is a circuit diagram of one type of compensator; and

Fig. 4 is a similar view of a modified form of compensator.

Referring now to the drawings and to Fig. 1, 10 indicates generally a blower heater of the type common to industrial premises, meeting places, and the like, such heater usually being gas-fired and having a motor driven fan for directing strong heated currents of air.

When such a heater or heaters are installed in premises, it is evident that intermittent blasts of warm air are distributed throughout the premises with the result that if use is made of thermocouple fire alarm devices, distributed usually about the roof of the premises, these thermocouple elements will be intermittently heated to such an extent as to generate a considerable potential. The potential thus generated normally would be sufficient to actuate an alarm

mechanism associated therewith with the result that an alarm would be given at each operation of the blower heater. Referring to Fig. 2, it will be seen that a plurality of alarm thermocouples indicated at 12, 14, 16, and 18 are connected in series through a relay 19 and a meter 20 whereby if the potential generated by these thermocouples in a closed circuit is sufficient to energize the relay 19, such relay will pick up its armature 21 and close contacts 22 serving to energize an alarm device 24 having a source of potential 25 in circuit therewith.

However, in order to neutralize the effect of the intermittent blasts of hot air supplied by the blower, a compensating device indicated generally at 30 is included in the circuit of the alarm thermocouples with the polarity of the compensator in opposed relation to the polarity of the alarm thermocouples. This compensator is preferably located immediately in front of the blower heater so that the hot air discharged by this heater can have a more pronounced effect on the compensator than on the alarm thermocouples. Thus, if the compensator is correctly adjusted, a potential will be generated thereby in opposition to the potential generated by the combined alarm thermocouples and of the same value so that the relay 19 is not energized.

Each alarm thermocouple element is of conventional character preferably, but not necessarily, a thermopile, being made up of a number of hot and cold junctions of dissimilar metal so arranged that when the hot junctions are at a temperature higher than the cold junctions, a potential will be generated.

The compensator element enclosed in the unit 30 comprises (Fig. 3) a thermocouple of like nature indicated at 35 made up of a number of joints of dissimilar metal and connected to terminals 36 and 37. These terminals 36 and 37 can be connected in the line 38 which serves to connect the alarm thermocouples in series. However, it will be noted that the polarity of the thermocouple 35 is reversed relative to the polarity of the alarm thermocouples so that the potential generated by the thermocouple 35 will buck the potential generated by the alarm thermocouples. Associated with the terminals 36 and 37 are a plurality of resistors 40, which can be connected selectively in parallel with these terminals by means of the switch 41 which has a sweep to engage the contact points between the resistors 40. These resistors may be of any suitable value, in practice it having been found that resistors of the nature of one ohm will suffice for ordinary operation. This sweep 41, however, can be moved to a position 42 in which position the resistors in effect are shunted out of the circuit with the result that the full potential generated by the thermocouple 35 will be introduced into the circuit of the alarm thermocouples. Likewise, if the sweep 41 is moved into contact with a point 44, the result will be that the thermocouple 35 is in effect short-circuited so far as its influence on the alarm circuit is concerned.

In Fig. 4 a modification of the compensator has been shown, such modification comprising a thermocouple 50 connected to terminals 51 and 52. Associated with this thermocouple 50 is a variable resistor 54 which can be operated either to introduce resistance in series with the thermocouple and the line 38 or to be shorted out of the circuit so that the full effect of the thermocouple 35 can be utilized. For example, if the compensator is connected in the line 38 as shown

in Fig. 4, and if the sweep 55 is in an intermediate position along resistor 54, the effect will be to introduce a resistance in series with the thermocouple 50 to vary the effective potential supplied by this thermocouple to the alarm circuit. However, if the sweep 55 is in the full position, it follows that all resistance has been eliminated from the circuit so that the full effect of the potential generated by the thermocouple 50 will be introduced into the circuit. Similarly, if the sweep is in the off position, the thermocouple 50 is in effect short-circuited so that the potential generated thereby will not be introduced in opposing relation to the alarm thermocouples.

In utilizing either compensator element as shown in Figs. 3 and 4, it will be evident that these devices can be adjusted by operation of the sweeps 41 or 55 while the blower heater is in operation until the effect of the compensating potential nullifies the effect of the potential generated by the alarm thermocouples, which condition will be evidenced by the meter 20. Furthermore, it will be evident that if a single compensator is not sufficient to produce the desired results, additional compensators can be introduced into the circuit by installing the same in the alarm circuit and positioned adjacent the blower heater, or in any other advantageous location about the premises.

With the compensator adjusted to nullify the potential generated by the alarm thermocouples while the blower heater is in operation, an alarm can still be given if a condition of fire occurs since the heat supplied by such fire will serve to increase the potential generated by one or more of the alarm thermocouples thereby upsetting the balanced condition in the alarm circuit and causing the relay 19 to close the contacts 22.

From the foregoing it will be seen that the present invention provides improved compensation for fire alarm systems installed in premises employing heaters of the intermittent blast type. It will be evident that modifications beyond the illustrated embodiments can be made, and accordingly any limitations imposed on the invention are to be only those set forth in the following claims.

What is claimed is:

1. In a system for detecting fire in a supervised region of premises which are subjected intermittently to non-hazardous heat from a non-hazardous, intermittent heat source, in combination, a plurality of alarm thermocouples spaced apart about said supervised region for generating a voltage in response to rises in the temperature in said supervised region of said premises, a compensator thermocouple located closer to said non-hazardous source than is any one of said alarm thermocouples, said compensator thermocouple being positioned to receive more heat from said non-hazardous source during its operating intervals than does any of said alarm thermocouples, alarm means, alarm actuating means connected in a series circuit with said alarm thermocouples and said compensator thermocouples, said alarm thermocouples being in a voltage additive relationship to one another, but in a voltage opposing relationship to said alarm thermocouple, said alarm thermocouple being adapted to generate a great enough voltage in response to heat from said non-hazardous source that if not attenuated, said voltage would over-compensate for the voltage generated by said alarm thermocouples, in response to heat from said non-

hazardous source, and a variable resistor connected across the terminals of said compensator thermocouple in shunt therewith, said resistor being adjusted to a value of resistance which will attenuate the effective voltage from said compensator thermocouple to a value which will substantially balance the voltage from said alarm thermocouples during intervals when heat is received solely from said non-hazardous source and thereby suppress actuation of said alarm, but said value of resistance being small enough to limit the possible effective voltage from said compensator thermocouple to a value small enough to enable said alarm thermocouples to actuate said alarm when fire occurs in said supervised region, even when heat is being received by said compensator thermocouple from said non-hazardous heat source.

2. In a system for detecting fire in a supervised region of premises which are subjected intermittently to heat from a non-hazardous heat source, in combination, a plurality of alarm thermocouples connected additively in series and spaced apart about said supervised region of said premises, for generating a voltage in response to rises in the temperature in said supervised region, a compensator thermocouple spaced apart from said alarm thermocouples, said compensator thermocouple and said alarm thermocouples being positioned so that said compensator thermocouple is closer to said non-hazardous heat source than is any one of said alarm thermocouples and receives more heat originating in said non-hazardous source than does any of said alarm thermocouples, alarm actuating means connected in a series circuit with said alarm thermocouples and said compensator thermo-

couple, said compensator thermocouple being connected in said series circuit with a polarity opposed to that of said alarm thermocouples, a plurality of resistors connected in series combination, a plurality of stationary contacts individually connected to junctions between said resistors, a movable contact member adapted selectively to engage any one of said stationary contacts, means connecting one terminal of said compensator thermocouple to one end of said series combination of resistors, means connecting its other terminal to said movable contact member, said movable contact member being so positioned as to engage one of said stationary contacts which will provide an effective resistance across the terminals of said compensator thermocouple great enough so that during intervals when heat is being received solely from said non-hazardous source the voltage from said compensator thermocouple is great enough to suppress actuation of said alarm by said alarm thermocouples, but said resistance being small enough to limit the possible effective voltage from said compensator thermocouple to a value small enough to enable said alarm thermocouples to actuate said alarm when fire occurs in said supervised region, even when heat is being received by said compensator thermocouple from said non-hazardous heat source.
